UNITED STATES PATENT OFFICE

ALBERT M. JOHNSON, OF ROCKFORD, ILLINOIS, ASSIGNOR TO BARNES DRILL CO., OF ROCKFORD, ILLINOIS, A CORPORATION OF ILLINOIS

HONING MACHINE

Application filed November 13, 1925. Serial No. 68,753.

The invention relates to a machine for honing the cylinders of internal combustion engines and similar hollow cylindrical bodies such as bearings, bushings, air brake cylinders, hydraulic cylinders, etc.

Heretofore internal combustion engine cylinders, etc. have been finished by what is generally known as internal grinding. According to this practice, relatively coarse grinding wheels are employed, and not only is difficulty experienced in producing a surface free from high spots, but a rough finish is produced which is worn smooth only after a long period of use.

The object of the invention generally stated is to produce a machine of advantageous character for finishing engine cylinders and the like by a honing operation as distinguished from internal grinding, in which fine abrasive stones of substantial length press against the surface to be finished, uniformly throughout its periphery, and are simultaneously reciprocated and rotated with the result that high spots and other inequalities are quickly removed and an extremely smooth finish produced.

More specifically the invention has for its object the production of a machine of the character indicated in which a rotating honing tool may be continuously reciprocated at high speed but without undue shock or strain.

A further object is to provide for varying the speed of reciprocation relative to the speed of rotation as desired.

A further object is to provide improved means for supporting the work for movement into and out of operative association with the honing tool.

The objects of the invention thus generally stated, together with other and ancillary advantages are obtained by the construction and arrangement herein set forth, but it is contemplated that various changes may be made by those skilled in the art without departing from the spirit and scope of the invention as expressed in the appended claims.

Figure 1 of the drawings is a front elevational view of a honing machine embodying my invention.

Fig. 2 is a fragmentary side elevational

view of the same, a portion of the driving means being shown in section.

Fig. 3 is a fragmentary horizontal sectional view taken approximately in the plane of line 3—3 of Fig. 2 but on an enlarged scale.

Fig. 4 is a fragmentary vertical sectional view showing the spindle-reciprocating cam.

Fig. 5 is a fragmentary vertical sectional view showing a slightly different arrangement of the driving means employed when a slow speed reciprocation of the spindle is desired.

The machine comprises a base 7 having a column or standard 8 rising from one end thereof and supporting at its upper end a head 9 in which is mounted for rotation and reciprocation a vertically disposed spindle 10. The lower end of the spindle carries a suitable honing tool 11 and the upper end of the spindle receives the application of power through the medium of a drive means generally designated by the numeral 12 having a gearing connection 13 with the spindle to rotate it and a suitable driving connection with a cam means 14 to reciprocate the spindle. The work is supported on the column 8 through the medium of a table 15 which is arranged to be raised and lowered to carry the work into and out of engagement with the honing tool 11 by means such as an air or other fluid pressure operated mechanism 16.

The spindle 10 is mounted for reciprocation and rotation in the head 9 at the forward side thereof. Herein a suitable bearing 17 is provided in the upper portion or crown of the head to receive the spindle, and near the lower portion of the head a bearing 18 is provided to receive a sleeve 19 in which the spindle is journaled, the sleeve being held against longitudinal movement on the spindle. A rack 20 rigid with the sleeve is engaged by a pinion 21, and a cross shaft 22 journaled in the head is equipped with a hand wheel 23. By this means the spindle may be adjusted manually.

The honing tool 11 at the lower end of the spindle may be of any suitable or preferred character. Herein it comprises a fixture 24 carrying honing stones 25 of substantial length arranged in circumferentially spaced relation and adapted when inserted into the

cylinder or other piece of work to expand radially into engagement with the inner peripheral surface of the cylinder. Inasmuch as this honing tool forms no part of my invention, it is deemed unnecessary to illustrate and describe its construction in detail.

The driving means 12 is herein shown as comprising a shaft 26 journaled transversely of a housing 27 suitably formed at the upper 10 end of the head 9 at the rear side thereof. The shaft is mounted in opposite walls of the housing 27 in suitable bearings 28 and 29, and one end of the shaft protrudes from the housing and is connected with a suitable 15 source of power, a pulley wheel 30 being herein shown fast on the shaft. Power may be communicated from this shaft to the spindle 10 so as to drive it in one direction only; but the means herein shown embodies 20 a reversing mechanism such that the spindle may be rotated in opposite directions at different speeds. Thus, within the housing 27 and in spaced relation on the shaft 26 are a pair of bevel gears 31 and 32, the latter being 25 smaller than the former. These bevel gears are loose on the shaft and constantly mesh respectively with a pair of bevel gears 33 and 34 fast on the rear end of a perpendicularly disposed driven shaft 35 which is suitably 30 journaled in the forward wall of the housing 27. The forward end of this shaft 35 has a bevel pinion 36 thereon meshing with a bevel gear 37 on a vertically disposed shaft 38 mounted at opposite ends in suitable bearings 39 and 39'; and between its ends the shaft 38 carries a pinion 40 meshing with a gear 41 splined on the spindle 10 and bearing in the crown 41' (Fig. 4).

The gears 40 and 41 constitute the gearing connection 13 between the driving means and the spindle, and it will be seen that the spindle is arranged to be driven in one direction or the other by such connection depending upon whether the drive is through the bevel gear 33 or the gear 34. Also, it will be observed, the two sets of gears 31 and 33 and 32 and 34 are differently proportioned so as to drive the spindle at different speeds. To control the direction of drive a pair of friction clutches 42 and 43 are associated with the gears 31 and 32, and these friction clutches are arranged to be operated by an intermediate clutch shifting device in the form of a collar 44 with which is associated a bell 45 crank lever 45. This lever has one arm 46 operatively engaging a groove in the collar 44 and its other arm 47 connected by means of a link 48 with a lever arm 49 on the upper end of a vertical shaft 50. The shaft 50 is mounted in suitable brackets 51 and 52 at one side of the head 9, and near its lower end the shaft carries a hand lever 53 extending forwardly along the side of the head into a convenient position for manipulation.

To prevent an over-running of the mecha-

nism when the clutch is shifted into neutral position, I provide a brake device consisting of a shoe 54 mounted on a lever 55 adjacent the end thereof which is pivoted at 56 to the rear wall of the housing 27. A coiled spring 57 is interposed between the other end of the lever and the housing, and tends normally to apply the brake shoe to a drum 58 which in the present instance is formed integral with the bevel gear 31. The free end of the lever 55 has a pair of spaced cam surfaces 59 and 60 at opposite sides of a cut-away portion or recess 61, and the arm 46 of the bell crank 45 is extended rearwardly and equipped with a roller 62 which is adapted to engage with the cam surfaces 59 and 60 when the clutch collar 44 is moved in one direction or the other to operate the clutches 42 or 43. In the neutral position of the clutch collar 44, the roller 62 enters the recess 61 in the lever 55, thus permitting the spring 57 to apply the brake element to the drum 58.

If it is desired to rotate the spindle in one direction only, the bevel gears 32 and 33 together with the associated friction clutch 43 may obviously be omitted; also the cam surface 59 on the lever 55 would be omitted.

While the spindle 10 is being driven through its gearing connection 13 with the driving means, power is also communicated to the spindle to cause it to reciprocate during such rotation through the medium of the cam means 14. This means comprises (Fig. 4) a cylindrical cam member 63 having a continuous cam groove 64 therein with which a roller 65 engages. The cam member 63 is adjustably secured to the upper end of the spindle 10 and the roller 65 is journaled on a stub shaft 66 journaled in a cylinder 67 in which latter the cam is rotatably mounted. Preferably the cam groove 64 is shaped so as to effect the movement of the spindle in opposite directions at a uniform rate, and means is provided, as hereinafter described, to cushion the spindle at each end of its movement.

The connection between the cam 63 and the spindle comprises in the present instance a recessed collar 68 rigidly secured, as by means of screws 69, to the upper end of the cam member. Fitting in this collar is a clamping nut 70 having a screw-threaded engagement with the upper end of the spindle. A lock nut 70' is provided to hold the parts in the desired position of adjustment. To insure that relative rotation between the spindle and the cam member shall be prevented, the parts are splined together, this arrangement permitting of the convenient adjustment of the cam member longitudinally of the spindle as may be desired. The cam roller shaft 66 is herein shown as mounted in a radially extended housing 71 bolted to one wall of the cam cylinder 67. A roller bearing 72 is preferably provided between the inner end of the shaft and the housing; and a ball bearing 72' is pro-

vided at the outer end of the shaft. Between these two sets of bearings is a separating or spacing sleeve 72^a.

While it will be apparent that rotation of the cam member 63 relative to the roller 65 will cause the spindle to reciprocate, I preferably arrange to revolve the roller about the cam so that when desired the speed of operation of the cam and hence the rate of reciprocation may be substantially increased. In Figs. 1 to 4, I have shown for this purpose means for driving the cam cylinder 67 and hence the roller 65 in a direction opposite to that of the spindle so as to increase the rate of reciprocation of the latter by increasing the relative speed between the cam member and its roller. This means comprises a pinion 73 on the upper end of the shaft 38 meshing with an idler gear 74 on a shaft 75, the latter also having rigid therewith a pinion 76 meshing with a gear 77 fast on the cylinder 67.

The cylinder 67 is mounted for rotation in a housing 78 mounted on the head 9 and serving to enclose the gear train 73, 74, 76 and 77. Thus, referring to Fig. 4, said cylinder 67 is provided with a radial flange 79 slidably engaging in an annular way 80 formed at the upper end of the housing 78. A ring 81 bolted to the housing overlies the flange 79 to complete the bearing for the flange. The arrangement is such that the cylinder 67 when driven by said gear train 73, 74, 76 and 77 rotates at relatively slow speed in a direction opposite to the direction of rotation of the spindle. Hence, while the spindle rotates slowly, the relative speed between the cam member 63 and its cylinder 67 is substantially greater and the rate of reciprocation of the spindle is accordingly relatively high.

It is sometimes preferred on the other hand to rotate the spindle at high speed while it is reciprocated slowly. In this event, the drive may be directly from the pinion 73 to the gear 77 omitting the idlers 74 and 75. Thus, referring to Fig. 5, the pinion 73 is displaced by an interchangeable pinion of larger diameter, and in such event the new pinion is shifted upwardly on the shaft 38 so as to engage directly with the gear 77. This may be accomplished in any suitable way as by placing a spacing collar near the upper end of the shaft 38 beneath the pinion 73. It will be seen that by this arrangement the cylinder 67 will be driven in the same direction as the spindle 10 and hence the cam member 63, but at a different speed, the arrangement being such that the spindle rotates at the same rate as before but the rate of reciprocation imparted thereto is substantially slower.

The cam groove 64 in the cam member 63 is so shaped as to reduce to a minimum the dwell at the upper and lower limits of the spindle stroke; and to overcome the shock at each end of the stroke and thus insure smoothness of

operation I provide cushioning means receiving the upper and lower thrusts of the spindle as it approaches the ends of its movements. Herein this means comprises in the case of the upper limit of movement a bonnet 82 rigidly mounted on the upper end of the cam cylinder 67 and enclosing the upper end of the spindle projecting above the cam member 63. This bonnet is preferably so shaped in its lower portion as to be slightly larger in diameter than the diameter of the cam, and its upper end is reduced in diameter according to the diameter of the spindle. Thus it constitutes a compression chamber acting as the spindle approaches the upper limit of its movement to receive the thrust of the latter and assists in changing the direction of spindle reciprocation without shock.

In the case of the lower limit of movement, the inertia is absorbed in the present instance by means of a coiled compression spring 83 surrounding the spindle and seated in a recess 84 provided in the lower end of the cam member 63. The lower end of this spring bears against the crown gear 41, which latter in turn bears against the head 9 within the crown gear casing 41^a. This construction also serves to hold the gear 41 against vertical movement. The arrangement is such that the spring 83 becomes effective as the spindle approaches its lowermost position, thus assisting the cam to reverse the direction of the spindle without jar or shock.

It will be observed that by removing the bonnet 82 access to the cam member may readily be had for purposes of adjustment. Also, the roller housing 72 may be readily removed from the cylinder 67 when it is desired to replace the cam member by another to vary the length of stroke of the spindle.

The table 15 for supporting the work may be of any suitable character, that herein shown being mounted on a knee 85 which in turn is mounted on ways 86 and 87 for up and down sliding movement. The table 15 is shown as provided with a block 88 in the upper face of which suitable ways 89 are provided in which a slide 90 is supported for reciprocating the work A. The latter, in the present instance, is shown in the form of a cylinder block for internal combustion engines, suitably secured upon the slide 90. The block may be formed with an elongated channel or trough 88^a beneath the slide 90, and the latter has apertures 90^a therein beneath the cylinders of the work A. Hence the honing tool may pass through and beyond the work, and the grindings and coolant or lubricant supplied (in any suitable manner, not shown) may pass downwardly into the channel.

Means is provided for adjusting the slide in the block 88 to position the cylinders successively beneath the honing tool 11. This means may comprise a pinion 91 mount-

ed on the slide 90 and projecting from one edge thereof so as to mesh with a rack 92 on the block 88. The pinion 91 is rigid with a crank shaft 93 having a crank arm 94 whereby the pinion may be rotated to adjust the slide and thereby the work A. A suitable clamping device 95 may be provided to lock the slide in any desired position of adjustment.

10 Pressure fluid actuated mechanism 16 is herein employed to raise the work A into operative association with the honing tool and to lower the work to remove it from the honing tool. This mechanism comprises in 15 the present embodiment a cylinder 96 having a piston 97 therein and a valve controlled means for supplying and exhausting motive fluid such as air to and from the cylinder. 98 indicates a supply connection leading to 20 a valve 99 which is adapted to control the supply of air to the lower end of the cylinder 96 by means of a pipe 100 and also to permit the supply of air to the upper end of the cylinder by means of a pipe 101 for the purpose of forcibly lowering the work. The 25 valve 99 may be of any suitable character, that herein shown being arranged to be operated by a foot lever 102 having a pawl 103 adapted to engage with a star wheel 104 fast on an operating shaft 105. A spring 106 restores the lever 102 to its initial position. The arrangement is such that when the work is in its lowermost position ready to be raised into engagement with the honing tool, a depression of the lever 102 will operate the 30 valve 99 to admit through the pipe 100 motive fluid to the lower end of the cylinder beneath the piston while permitting air to exhaust through the upper end of the cylinder 40 through the pipe 101; and when it is desired to lower the work, the next depression of the lever 102 will operate to admit motive fluid to the upper end of the cylinder through the pipe 101 and permit it to exhaust from 45 the lower end of the cylinder through the pipe 100. The work supporting table is thus raised and lowered through a fixed range of movement, but it will be remembered that the spindle 10 is adjustable to vary the intermediate position of the honing tool by adjusting the position of the cam member 63 on the upper end of the spindle. In practice, the clutch lever 53 may be operated into neutral position when the honing tool is at 50 its uppermost position so as to facilitate the disengagement of the work from the honing tool. Such stopping of the spindle in its uppermost position is facilitated by the brake device 54, 58 which operates, it will 55 be remembered, when the clutch is thrown into neutral position to stop the bevel gear 33 and thereby the driven shaft 35.

It will be seen that I have produced a honing machine in which the honing tool 60 may be rotated in either direction at different

speeds while at the same time reciprocation is imparted to the honing tool at either high or low speed as desired; in which the reciprocation is effected with a substantial absence of shock or jar on the machine; in which the drive mechanism is under convenient and positive control; and in which the work is easily and conveniently moved into and out of operative association with the honing tool. The construction employed is relatively simple and the driving mechanism is readily accessible.

I claim as my invention:

1. A machine of the class described comprising, in combination, a tool-carrying spindle, means for continuously reciprocating said spindle, means including a compression chamber for cushioning the spindle at one end of its reciprocatory movement, and means including a spring for cushioning the spindle at the other end of its reciprocatory movement.

2. A machine of the class described having a tool-carrying spindle, means for reciprocating the spindle, and means forming at the upper end of the spindle a compression chamber operating to cushion the spindle as it approaches its upper limit of movement.

3. A machine of the character described having a tool-carrying spindle, and means for reciprocating the spindle including a cylindrical cam member rigidly secured thereto, a rotatable cylinder in which said cam member is reciprocable and also rotatable, said cam member having a cam groove and a roller mounted in the cylinder and engaging in said groove, whereby rotation of said cylinder effects a reciprocatory movement of said spindle.

4. A machine of the character described comprising a tool-carrying spindle, a cylindrical cam member rigid with the spindle, a cylinder in which said cam member is mounted for rotational and reciprocatory movements, a roller mounted in said cylinder and operatively engaging said cam member, and means for rotating both the cam member and the cylinder at different speeds, to produce relative reciprocatory movement therebetween.

5. A machine of the character described comprising a tool-carrying spindle, a cylindrical cam member rigid with the spindle, a cylinder in which said cam member is mounted for rotational and reciprocatory movements, a roller mounted in said cylinder and operatively engaging said cam member, and means for rotating both the cam member and the cylinder in opposite directions, to impart a relatively high speed of reciprocation to said spindle.

6. A machine of the character described comprising a head, a spindle reciprocable and rotatable in said head and adapted to

carry a tool, a cam member rigid with the spindle, a cylinder in which said cam member is rotatable and reciprocable, said cylinder being rotatably mounted on the head, 5 and means for rotating the spindle and said cylinder, whereby relative longitudinal movement between said cylinder and said spindle is produced.

7. A machine of the character described 10 comprising a head, a spindle adapted to support a tool and mounted in said head for reciprocation and rotation, a driven gear element in the head and splined on the spindle to drive it, a cylindrical cam member fast 15 on the spindle, a rotatable cylinder in which said cam member is mounted and having a part operatively engaging with the cam member whereby to cause the cam member to reciprocate in its rotation, and means for rotating said cylinder, to increase or decrease 20 the speed of reciprocation of said spindle relative to said cylinder.

8. A machine of the character described 25 having a tool-carrying spindle, means for reciprocating the spindle including a cylindrical cam member rigid therewith, a rotatable cylinder in which said cam member is mounted and having a part operatively engaging therewith, and a driven shaft having 30 separate gearing connections with the spindle and with said cylinder, to effect relative rotation and reciprocation therebetween.

9. A machine of the class described having 35 a reciprocating tool-carrying spindle, a cam member on said spindle, a bearing for said cam member adapted to permit relative movement between said member and said bearing longitudinally of said spindle, and a housing extending endwardly of said bearing 40 effecting an enclosure of the portion of said spindle endwardly of said cam member, and also of said cam member during a portion of the reciprocating movement thereof.

10. A machine of the class described having 45 a reciprocating tool-carrying spindle, a housing enclosing an end portion of said spindle, a bearing supported endwardly of said housing in sealed communication therewith, and a member secured on said spindle 50 for reciprocating movement in said bearing, said member functioning as a piston to effect compression of air in said housing with the inward movement of said spindle.

11. In a machine of the character described, 55 the combination of a tool-carrying spindle, a cam member mounted on and rotatable with said spindle, an element having operative engagement with said cam member to impart longitudinal movement to said spindle, said element being supported for 60 rotary movement about the axis of said spindle, means for rotating said spindle, and means for rotating said element.

12. In a machine of the character described, 65 the combination of a tool-carrying

spindle, a cam member mounted on and rotatable with said spindle, an element having operative engagement with said cam member to impart longitudinal movement to said spindle, said element being supported for 70 rotary movement about the axis of said spindle, and means for selectively rotating said element in like direction and in opposite direction to said spindle.

13. In the machine of the character described, 75 the combination of a tool-carrying spindle, a cam member mounted on said spindle in non-rotative longitudinally adjustable relation thereto, an element having operative engagement with said cam member to impart longitudinal movement to said spindle, said element being supported for rotary movement about the axis of said spindle, means for rotating said spindle, and means for rotating said element.

14. In a machine of the class described, the 80 combination of a tool-carrying spindle, means for rotating said spindle, means for simultaneously imparting longitudinally reciprocating movement to said spindle including a cylindrical cam member and a relatively stationary element engaged therewith, said cam member having a continuous cam groove effective to cause the movement of said spindle at a substantially uniform rate in each 85 direction and without appreciable dwell at the ends of the reciprocating strokes, and means for cumulatively resisting the movement of said spindle toward the end of each stroke adapted to substantially counterbalance the inertia of movement of said spindle at the end of each stroke.

In testimony whereof, I have hereunto affixed my signature.

ALBERT M. JOHNSON.
